UNITED STATES PATENT OFFICE.

PETER GRABLER, OF CLEVELAND, OHIO, ASSIGNOR TO SOLOMON HIMMEL, OF BALTIMORE, MARYLAND.

CASTER.

1,175,885.

Specification of Letters Patent. Patented Mar. 14, 1916.

Application filed April 13, 1915. Serial No. 21,039.

To all whom it may concern:

Be it known that I, PETER GRABLER, a citizen of the United States, residing at Cleveland, in the county of Cuyahoga and State 5 of Ohio, have invented new and useful Improvements in Casters, of which the following is a specification.

This invention is an improved caster of the type usually employed for supporting, 10 and facilitating the moving of movable articles, such as furniture, sliding doors and the like, although its use is not limited to any particular or specific class of such movable articles.

15 One of the objects of the invention is to provide a caster, constructed to permit attachment to the article which it is intended to support, in such manner that all of the working parts are concealed, except 20 so much of the supporting roller, as is necessary to raise said article clear of the surface from which it is supported.

A further object is to provide means for 25 adjusting the supporting roller with respect to the article to which the caster is attached, whereby said article is raised or lowered, and to provide the same with means to permit a swiveling movement of the roller, when the article is moved, without affecting 30 the adjustment.

35 A further object is to provide means for effectively locking the parts in any adjusted relation, so as to maintain the desired adjustment, and without affecting the swiveling movement of the roller when the article is moved.

The invention will be hereinafter fully set forth and particularly pointed out in the claims.

40 In the accompanying drawing:—Figure 1 is a side elevation of a portion of a sliding door, with my improved caster attached thereto. Fig. 2 is a similar view with the locking member removed. Fig. 3 is a bottom plan view. Fig. 4 is a side view of the caster detached. Fig. 5 is a longitudinal sectional view.

Display racks of the rotary inclosed type, for displaying ready made garments and the like, have come into general use, and are usually constructed with glass walls or panels, so that the goods on display may be readily seen by prospective customers passing the same, the front wall of a case or

compartment being usually made up of slide- 55 able doors or sections, which may be moved to one side, to permit access to the articles within the case. In order that the articles on display may be protected from dust, and the like, it is desirable, and in fact im- 60 portant, that a substantially close contact be maintained between the edges of the door and the surfaces with which they co- 65 operate. The present invention is designed to meet these requirements, and in the drawings is illustrated as attached to a door of the character above specified, but its use is not limited to slideable doors or panels, it being capable of use in connection with any article to which a caster may ordinarily be 70 applied.

Referring to the drawings, 10 designates a portion of the rail of a sliding door or panel provided with a socket 11 leading in from the lower edge thereof. Intersecting the 75 socket 10, and leading in from one face of said rail is a recess 12 provided with an arcuate offset portion 13. Said recess is covered by a locking plate 14 provided with slots 15, through which are passed attaching 80 screws 16, 17, said plate being provided with an inwardly extended locking pin 18.

The caster comprises a forked caster member 20 supported by a caster wheel 21, and attached by means of a suitable pin or 85 swivel 22 to an adjusting member 23, the pin or swivel 22 being of sufficient length to permit of the insertion of antifriction 90 balls 24 between the supporting member and the caster member. The supporting mem- 95 ber is provided with external screw threads 25, designed to mesh with corresponding threads 26 upon the interior of a tubular casing 27, and located near the upper open end of said casing. The supporting member 95 is provided with an annular flange 28 pro- 100 vided with notches 29 which are shaped to be engaged by the locking pin 18. The lower edge of the casing 27 is provided with flanges or ears 30, designed to rest against 105 the lower edge of the rail 10, screws 31, or other attaching means, being employed to secure the casing to said rail. When the caster is used upon a door as above de- 110 scribed, it may, under some conditions, be desirable to have the roller 21 run in a channel iron 32, preferably of U-shaped track 32, illustrated in the drawings.

- In practice the threaded portion of the supporting member 23 is engaged with the complementary threaded portion of the casing 27, and said casing is then secured in 5 position within the socket 11. The supporting member 23 is then rotated to cause the roller 21 to protrude from the casing the desired extent, such rotation being effected by engaging the notches 28 and moving the 10 supporting member in the desired direction, by means of a suitable tool, such as a screw driver. When the desired adjustment has been obtained, the locking plate 14 is secured in position, with the locking pin 18 in engagement with one of said notches. In 15 this manner the parts are locked in adjusted position and the desired relation of the parts is maintained. Should it become necessary or desirable to change the adjustment, the screws 16 and 17 are loosened, and the plate 14 moved upwardly a sufficient distance to disengage the locking member 18 from the notch 29 in which it is then located, and then by swinging said plate to 20 one side on the screw 16 as a pivot, the pin 18 will move into the offset 13, and the recess 12 will be exposed. By engaging the notches 29 with a screw driver or other 25 similar instrument, the member 23 may be rotated to bring the caster 21 in the desired relation with respect to the edge of the door. By then returning the plate to its proper position, the parts will be again locked.
- From the foregoing it will be seen that I have produced an adjustable caster that is simple in construction, and in which the working parts are concealed, nothing being exposed except so much of the roller 21 as 30 is necessary to support the door clear of the surface on which the caster runs. It will also be readily seen that the caster may freely swivel under the operation of the door, without disturbing any adjustment that may have been made.
- It will be further observed, that where a plurality of casters are employed to sustain a movable article, they may be readily adjusted, so as to maintain said article perfectly level, and in the case of a door, so that the said door may move without binding.
- Having thus explained the nature of my invention and described an operative manner of constructing and using the same, although without attempting to set forth all of the forms in which it may be made, or all of the forms of its use, what I claim is:
1. An improvement in casters comprising a caster member provided with a roller, and a casing for attaching the caster member to the article to be supported, said casing inclosing substantially all of said caster member and a portion of the roller thereof, the 55 outer end of said casing extending beyond the plane of the outer end of said caster member, the inner end of said casing and said caster member each provided with integral means coöperating to adjustably unite them to normally prevent relative longitudinal movement of the casing and caster member in either direction, said caster member being rotatable within said casing.
2. An improvement in casters comprising a supporting member, a caster member provided with a roller, a swivel connection between said caster member and said supporting member, and a container for attaching the supporting member to the article to be supported, said container extending from the inner end of the caster member outwardly beyond the axis of the roller, said container being provided at its inner end with threads adjustably engaging corresponding threads of the supporting member to normally prevent relative longitudinal movement thereof in either direction, the outer end of said container extending beyond the plane of the outer end of said supporting member.
3. An improvement in casters comprising a supporting member, a caster member provided with a roller, a swivel connection between said supporting member and said 95 caster member, a casing encircling said supporting member and inclosing substantially all of the caster member and a portion of the roller thereof, said casing and said supporting member having complementary means for effecting a relative adjustment, and means for locking the parts in any desired 100 adjusted relation.
4. An improved caster comprising a caster member provided with a roller, a supporting member having a swivel connection with said caster member and provided with a notched flange, a casing inclosing said caster member and said supporting member, a threaded connection between said supporting member and said casing, and means for engaging said notched flange to lock the 105 supporting member from rotation.
5. An improvement in casters comprising a supporting member, a caster member provided with a roller, a swivel connection between said supporting member and said 115 caster member, a casing having a threaded engagement with said supporting member, said casing inclosing substantially all of the caster member and a portion of the roller thereof, and a locking device for engaging 120 said supporting member.
6. An improved caster comprising a caster member provided with a roller, a supporting member having a swivel connection with said caster member and provided with a notched flange, a casing inclosing said caster member and said supporting member, and having a threaded engagement with the sup- 125

porting member, and a movable locking member provided with a pin for engaging said notched flange.

7. The combination with a movable member provided with a socket therein, and a recess intersecting said socket, a casing within said socket, a supporting member adjustably engaging said casing, and a caster member provided with a roller and having a swivel connection with said supporting member, said casing inclosing substantially all of the caster member and a portion of the roller thereof, and a locking member extending through said recess to engage said supporting member.

8. The combination with a movable member provided with a socket therein and a recess intersecting said socket, of a casing within said socket, a supporting member also within said socket and adjustably engaging said casing, said supporting member being provided with a notched flange, a caster member within said casing and having a swivel connection with said support-

ing member, a roller for supporting said caster member, and a locking member provided with a pin extending through said recess to engage said notched flange.

9. An improvement in casters comprising a cylindrical casing, a caster member provided with a roller to rotate about a horizontal axis within said casing, and partly projecting beyond one end of said casing, a supporting member mounted to be rotatably adjustable in the other end of said casing and having a part projecting from the casing, a swivel connection between said caster member and said supporting member, and means engaging the projecting part of said supporting member to hold it in fixed relation with the casing.

In testimony whereof I have hereunto set my hand in presence of two subscribing witnesses.

PETER GRABLER.
